WALTER MAECHLER, OF CHICAGO, ILLINOIS, ASSIGNOR TO LEE E. DANIELS, OF CHICAGO, ILLINOIS.

MEAT-TENDERING IMPLEMENT.

1,357,069.

Specification of Letters Patent.

Patented Oct. 26, 1920.

Application filed December 3, 1919. Serial No. 342,078.

To all whom it may concern:

Be it known that I, WALTER MAECHLER, a citizen of the United States, residing at 1821 Berteau avenue, Chicago, in the county 5 of Cook and State of Illinois, have invented a new and useful Improvement in Meat-Tendering Implements, of which the following is a specification.

My invention relates to improvements in 10 the class of meat-tenderers in which the implement comprises a handle-equipped head rigidly carrying a plurality of stems terminating in cutting edges for perforating meat to tender it by cutting its fibers.

15 The object of my invention is to provide a meat-tenderer in the class referred to of a superior construction enhancing its efficiency of operation.

In the accompanying drawing, Figure 1 20 is a perspective view of the implement; Fig. 2 is a bottom plan view of the same; Fig. 3 is an enlarged section on line 3—3, Fig. 2; Fig. 4 is an enlarged broken plan view of the intermediate plate in Fig. 3, showing 25 the central aperture, and Fig. 5 is an enlarged perspective view of the screw for said aperture; Fig. 6 is an enlarged broken view of one of the plurality of similar cutting stems, showing a preferred form there- 30 of; Fig. 7 is a section on line 7—7, Fig. 6; Fig. 8 is a view like that presented in Fig. 3, but showing a modification, and Fig. 9 is an enlarged broken plan view of the plate 35 in Fig. 8, showing the shape of the perforations therein into which the cutting-stems are driven.

My improved implement comprises, generally described, a cap fitting about one or more numerously perforated head-forming plates, through the perforations in which are driven, to abut at their inner, blunt ends against the inner face of the cap, stems of general cylindrical shape, each beveled on opposite sides of its outer end to form a 45 cutting edge; and a handle is rigidly secured in place on the cap by a bolt passed centrally through the plate or plates and fastened by a nut.

In the construction most clearly illustrated in Fig. 3, a plurality of relatively thin numerously perforated plates are employed for the head. Of these plates three are shown at 9, 10 and 11; and the outermost is beveled about its edge. The cap 12,

which fits over the plates, is spun about the 55 beveled edge of the plate 11 to conform thereto and provide a shoulder at 13 confining the plates in the cap and sealing the latter against ingress of moisture and foreign matter. To produce a tight fit of the 60 cutter-stems 14, which may be formed of wire and suitably hardened, each is slightly enlarged in diameter in excess of that of the perforations, at the section 14^a which is 65 driven into coincident perforations in the successive plates to become tightly fastened in place therein. The handle 15 is rigidly secured centrally to the cap by a bolt 16 passed through the center of the two inner plates and cap, and is fastened by a nut 17 70 applied through the open handle-base, the slotted head of the bolt being covered by the plate 11 to shield it against lodgment in the slot of meat, which would tend to render the implement unsanitary. The 75 blunt ends of the cutter-stems abut against the inner face of the cap, and thus have a rigid stop presented to them. The bolt clamps the parts firmly together; and to prevent it from turning in screwing the 80 nut for tightening, the head of the bolt, which is countersunk in the hole, in plates 10 and 9 receiving it, is provided with laterally projecting lugs or wings 16^a to enter recesses 11^a in the said bolt-hole in plate 10 85 for confining the bolt against rotation.

The modified construction illustrated in Figs. 8 and 9 differs from the construction in Fig. 3 in forming the head of a single plate 18 of substantially the same thickness 90 as that of the described plurality of plates; and since the stem-perforations in a plate of that thickness will not yield as will those in the relatively thin plates, in driving the enlarged sections of the stems 14 through 95 them, they are provided in the elongated or oval form of the perforation 19 shown in Fig. 9, but slightly smaller in diameter than that of the stem-sections 14^a whereby the stems are tightened by driving them 100 into place, and are rigidly held against any tendency to rotate in their bearings. The head-forming plate 18 has its edge beveled, like the plate 11, to adapt the cap to be spun about it and form a shoulder 13, 105 as and for the purpose thereof described in connection with Fig. 3, with which the construction illustrated in Fig. 8 corresponds

except as to the one-plate head and the bolt-head being uncovered.

To apply the implement to its purpose the operator, grasping it at its handle, works it vertically against the meat to be tendered, thereby perforating the latter and cutting up the fibers. The stems pass through the meat without lacerating it, and the perforations tend to close up when the stems are withdrawn. Thus the meat is rendered tender without bleeding it, as is done by other tendering implements known to me, which hack, cut or maul the meat.

I realize that considerable variation is possible in the details of construction thus specifically shown and described, and I do not intend by illustrating specific embodiments of my invention to be limited thereto; my intention being in the following 20 claims to claim protection upon all the novelty there may be in my invention as broadly as the state of the art will permit.

I claim—

1. A meat-tendering implement comprising a cap, a plurality of independent head-forming plates in the cap having substantially alining openings therein, and cutting-stems having enlargements adapted to enter said openings and to be pressed into

engagement with the edges thereof to seat 30 therein.

2. A meat-tendering implement comprising a cap, a plurality of independent head-forming plates in the cap having substantially alining cutting-stem receiving-openings therein, certain of said plates having a central bolt-hole formed with lateral recesses, a bolt passing through said bolt-hole and provided with a winged head fitting in the recessed end of the bolt-hole, a handle 40 carried by the outer end of said bolt, and cutting-stems adapted to enter the openings in the plates and to be pressed into engagement with the edges thereof to seat 45 therein.

3. A meat-tendering implement comprising a cup-shaped member forming a cap, a head forming a closure for said cap and having cutting-stem-receiving openings of oval or elongated form therein, and cutting 50 stems having enlargements slightly larger than said openings and adapted to be driven into the same with their enlargements in engagement with the edges thereof to seat therein, said plate having a bolt-hole, a 55 bolt therein, and a handle carried by the outer end of said bolt.

WALTER MAECHLER.
